(57) **CLAIM**

The ornamental design for a lanyard with carabiner, as shown and described.

DESCRIPTION

FIG. 1 is a left side elevation view of a lanyard with carabiner showing our new design;

FIG. 2 is a right side elevation view thereof;

FIG. 3 is a left side elevation view thereof, showing the carabiner open;

FIG. 4 is a right side elevation view thereof, showing the carabiner open;

FIG. 5 is a back elevation view thereof;

FIG. 6 is a front elevation view thereof;

FIG. 7 is a top plan view thereof; and,

FIG. 8 is a bottom plan view thereof.

The broken lines represent the portions of the design that form no part of the claim.

The lanyard with carabiner is shown broken away in the middle to indicate that it has no specific length other than what is shown.

1 Claim, 4 Drawing Sheets
